UNITED STATES PATENT OFFICE.

CHARLES J. SCHIFFERLE, OF BERKELEY, CALIFORNIA.

RIFFLE.

Application filed November 19, 1923. Serial No. 675,577.

My invention relates to riffles and one of the objects of the invention is to provide a riffle embodying means for keeping the riffle active.

5 Another object of the invention is to provide means for introducing into the space between the riffle bars a diffused current of fluid, so as to keep the material collecting between the riffle bars in a mobile condition, 10 thus facilitating the settling of the heavier values and the onward passage of the lighter material.

My invention possesses other objects and features of advantage, some of which, with 15 the foregoing, will be set forth in the following description of the preferred form of my invention which is illustrated in the drawings accompanying and forming part 20 of the specification. It is to be understood that I do not limit myself to the showing made by the said drawings and description, as I may adopt variations of the preferred form within the scope of my invention as set forth in the claims.

25 Referring to the drawings:

Figure 1 is a plan view of a portion of a sluice in which my riffle is disposed.

Figure 2 is a vertical sectional view taken in a plane indicated by the line 2—2 of Figure 1.

Figure 3 is an elevation partly in vertical section of the nipple and shield forming part of my device.

35 My invention comprises a frame including the outer walls 2, 3, 4 and 5 and the transversely extending riffle bars 6, of which there may be as many as desired. Preferably these riffle bars are wider at the top than at the bottom, as shown in Figure 2. 40 The width of the frame is such as to substantially fill the sluice 7 in which it is placed.

Underlying the riffle frame is a flat casing 8 forming a reservoir, on the top wall 9 of which, the riffle frame is adapted to lie. This casing forms a reservoir for fluid, preferably water, introduced into it, preferably at one corner, thru a pipe 11 and flexible connection or conduit 12, which at 50 its other end, is connected thru the valve 13 into a conduit 14 thru which fluid is supplied from any suitable source. The valve 13 provides means for regulating the amount of fluid delivered to the reservoir.

55 Disposed between the riffle bars as shown

in Figure 1, are rows of nipples 16 each carrying a shield 17. The nipple is conveniently pressed from seamless brass tubing and is provided with a flange 18 adjacent one end to limit the penetration of the nipple into both the shield 17 and the wall 9 of the reservoir. When the parts are assembled this flange operates to space the edges of the shield from the surface of the wall 9. The nipple is secured in a suitably sized 60 aperture in the wall, by spinning over the edge, and the outer end of the nipple is provided with an aperture 19 thru which the fluid is discharged from the nipple. The shield 17 fits over the apertured end 65 of the nipple so as to diffuse the jet of liquid issuing therefrom and turn it backwardly toward the wall 9 in thin, flat streams. The shield consists preferably of a thin, square plate which is formed by 70 pressure, in suitable dies, to provide a central socket in which the nipple fits tightly, and narrow radially disposed passages 21 leading from the curved apex 22 toward the base of the shield. This is accomplished by 75 pressing portions of the plate, perpendicular to each edge, into substantial parallelism with similar portions on the opposite side, to form the socket. This operation also 80 folds the intervening portions together, on the diagonal lines, so that four narrow passages radiate from the socket.

The shields are preferably arranged on the nipples as shown best in Figure 1, so 85 that fluid emitted from the shield is distributed over the entire lower portion of the space between the riffle bars. This diffused 90 countercurrent of fluid entering from the bottom prevents the packing of material collecting between the riffle bars, keeping it in 95 a mobile state so that settling of the heavier particles is facilitated. The force of the diffused streams is, of course, regulatable by means of the valve 13.

When sufficient values have accumulated 100 between the riffle bars and a clean-up is to be effected, the riffle frame is lifted and the collected values allowed to wash down the sluice in the usual way, the flexible connection 12 permitting ready movement of the 105 frame.

My riffle is particularly valuable in placer mining and also finds a peculiarly valuable use on dredges which may list to one side or the other, since the construction of the 110

riffle is such as to tend to prevent accumulation on the low side, even if tipped somewhat out of the horizontal.

I claim:

- 5 1. A device of the character described comprising a plurality of spaced riffles, a reservoir below said riffles, nipples arranged on said reservoir between the riffles and shields on said nipples for directing the fluid from said nipples in a diffused current into the space between the riffles.
- 10 2. A device of the character described comprising a flat casing forming a reservoir, a plurality of riffles arranged on said casing, rows of nipples connected into the casing between the riffles, means for supplying the reservoir with fluid under pressure, and means for diffusing the fluid emitted from said nipples.
- 15 3. A device of the character described

comprising a frame having transverse members forming riffles, a casing forming a reservoir on which said frame is adapted to rest, nipples connected into the casing and disposed between the riffles and diffusion shields arranged on the nipples.

4. The combination with a sluice of a frame substantially filling the sluice from side to side and having members extending transversely across the sluice to form riffles therein, a flat casing forming a reservoir adapted to underlie the frame, nipples connected into the casing and disposed between the riffles, diffusion shields arranged on the nipples, and a flexible conduit connecting the reservoir with a source of fluid.

In testimony whereof, I have hereunto set my hand.

CHARLES J. SCHIFFERLE.
